UNITED STATES PATENT OFFICE.

HARRY BRETTLER, OF BROOKLYN, NEW YORK, ASSIGNOR TO IDEAL LIGHTING NOVELTY CO., A PARTNERSHIP OF SAID BRETTLER AND ARON HOLENDER, OF BROOKLYN, NEW YORK.

DESIGN FOR A PLATE FOR SMOKERS' SETS.

Application filed May 7, 1929. Serial No. 31,131. Term of patent 3½ years.

To all whom it may concern:

Be it known that I, HARRY BRETTLER, a citizen of the United States, and a resident of Brooklyn, county of Kings, and State of New York, have invented a new, original, and ornamental Design for a Plate for Smokers' Sets of which the following is a specification, reference being had to the accompanying drawing, forming a part hereof.

In the drawing, the single figure shows a perspective view of the design.

I claim:

The ornamental design for a plate for smokers' sets substantially as shown.

HARRY BRETTLER.
